[57] **CLAIM**

The ornamental design for a combined molding and molding cap, as shown and described.

DESCRIPTION

FIG. 1 is a fragmentary perspective view of a combined molding; and molding cap in accordance with my new design;

FIG. 2 is a top plan view thereof;

FIG. 3 is a fragmentary front elevational view thereof;

FIG. 4 is a fragmentary side elevational view thereof;

FIG. 5 is a fragmentary perspective view of a second embodiment of a combined molding and molding cap;

FIG. 6 is a top plan view thereof;

FIG. 7 is a fragmentary front elevational view thereof;

FIG. 8 is a fragmentary side elevational view thereof;

FIG. 9 is a fragmentary perspective view of a third embodiment of a combined molding and molding cap;

FIG. 10 is top plan view thereof;

FIG. 11 is a fragmentary side elevational view thereof; and, FIG. 12 is a sectional view taken along line 12—12 of FIG. 9.

The combined molding and molding cap has been broken on the end to indicate indefinite length.
